UNITED STATES PATENT OFFICE.

MARTIN L. SENDERLING, OF JERSEY CITY, NEW JERSEY.

WAGON-BRAKE.

SPECIFICATION forming part of Letters Patent No. 614,628, dated November 22, 1898.

Application filed December 18, 1897. Serial No. 662,387. (No model.)

To all whom it may concern:

Be it known that I, MARTIN L. SENDERLING, of Jersey City, in the county of Hudson and State of New Jersey, have invented a new and 5 useful Improvement in Wagon-Brakes, of which the following is a specification.

My invention relates to an improvement in wagon-brakes in which provision is made for holding the brake-shoe in contact with the 10 wheel-tire throughout the extent of the shoe whatever be the varying positions of the brake-supporting arm under different loads.

A practical embodiment of my invention is represented in the accompanying drawings, 15 in which—

Figure 1 is a view of the brake in side elevation, showing the spindle on the brake-supporting arm in section. Fig. 2 is a top plan view. Fig. 3 is a transverse section longitudinally of the brake-supporting spindle along the line 3 3 of Fig. 2, and Fig. 4 is a view in detail of the brake-regulating spring and its support.

As my present invention is confined to the 25 structure of the brake itself rather than to the brake-supporting arm and means for operating it, I have only shown in connection with the brake the brake-supporting spindle and a short section of the brake-supporting arm.

30 The brake-supporting arm is denoted by A, and the brake-supporting spindle, extending from the arm A in any well-known or approved manner, is denoted by a. The spindle is here shown as of tapered form, and the

35 brake is supported thereon by a socket-piece B, bearing at one end against a collar b and at its opposite end against a washer b', the several parts being held in position by a nut C, screwed onto the end of the spindle. The

40 socket-piece B is in the present instance provided with a shoe D for sustaining the wear due to the grinding contact between it and the tire, the said shoe D being removably secured to the wings of the socket-piece by bolts

45 d. As thus constructed the brake is at liberty to swing on the spindle a into such position as may be required to bring its face into a position substantially parallel with the tread of the wheel to which the brake is to be applied.

50 To hold the brake in an adjusted position where it will be the most effective under normal conditions and at the same time permit

it to adapt itself to abnormal conditions without straining the parts, I provide the following mechanism:

A collar E, provided with oppositely-extended flanges e e' and with an interiorly-screw-threaded boss e² for receiving a set-screw e³, is fitted to the base of the spindle a in proximity to the collar b. To the flanges e e' there is secured a flat plate or bar spring F, the free ends of which are adapted to rest upon lugs b² b³, extending from the socket-piece B upon opposite sides of the spindle a, as clearly indicated in Fig. 2. It follows that 65 when the collar E is fixed to the spindle the spring F will hold the brake by its engagement with the lugs b² b³ yieldingly in position against a rotary movement on the spindle a.

To adjust the brake to the proper tension 70 to do the most effective work requires simply the loosening of the set-screw e³ and the rotation of the socket-piece B, which, through the connection of the spring F, will cause the collar E to rotate therewith into such position as 75 to bring the face of the brake parallel with the face of the wheel, and then fasten the set-screw e³ to hold the parts normally in the adjusted position. This normal position may be one in which the face of the brake is parallel with 80 the face of the wheel when the wagon is loaded with an ordinary load, in which case if the wagon-body be spring-supported a lighter load or a heavier load would have a tendency to change the relative directions of the face of 85 the brake and face of the wheel with respect to one another. This, however, would be promptly accounted for whenever the brake was applied to the wheel by the yielding of the spring F at that end of the brake which 90 first engaged the face of the wheel, thereby permitting the entire face of the brake to be brought firmly into contact with the face of the wheel as though in its normal position.

It is obvious that changes might be resorted 95 to in the form and arrangement of the several parts without departing from the spirit and scope of my invention. Hence I do not wish to limit myself strictly to the structure herein shown and described; but

100 What I claim is—

1. The combination with a brake-supporting spindle and a brake mounted thereon in free rotary adjustment, the said brake being

provided with lateral projections upon opposite sides of its axis of rotary adjustment, of a spring-support mounted on the said spindle, a spring fixed to said supports and having its free ends in position to engage the said projections on the brake and means for locking the spring and its support in different rotary adjustments on the spindle, substantially as set forth.

10 2. The combination with a brake-supporting spindle and a brake mounted thereon, in

rotary adjustment, of a collar mounted on the spindle independently of the brake, means for locking the collar in different rotary adjustments on the spindle and a spring carried by the collar and having a bearing upon the brake upon the opposite sides of its axis of rotation, substantially as set forth. 15

MARTIN L. SENDERLING.
